UNITED STATES PATENT OFFICE.

LEON A. SYGLER, OF NEWARK, NEW JERSEY.

UMBRELLA.

1,397,466.

Specification of Letters Patent. Patented Nov. 15, 1921.

Application filed February 11, 1919. Serial No. 276,388.

To all whom it may concern:

Be it known that I, LEON A. SYGLER, a citizen of the United States, residing at Newark, in the county of Essex and State of New Jersey, have invented new and useful Improvements in Umbrellas, of which the following is a specification.

This invention relates to new and useful improvements in umbrellas, and has for its primary object to provide an umbrella in which the cover is of india rubber.

I am aware that it is not new to make the covering of an umbrella from india rubber, and I do not claim this phase of the invention, the novelty in the present case residing in the manner in which the said covering is constructed.

Referring to the drawings:—

Figure 1 is a perspective view of an umbrella the cover of which is constructed in accordance with the present invention.

Fig. 2 is a detail view of the cover partly in section.

Referring more particularly to the drawings, the reference character 5 designates the umbrella staff, and 6 designates the ribs or structures thereof, the bows being represented by the reference character 7.

The cover or top 8 is formed of a plurality of sheets 9 of india rubber which are triangular in form, the apex 10 of said triangular members being slightly curved to provide attachment to a cap 11. These triangular members are equal in dimension to the space between the ribs 6 when the umbrella frame is opened or stretched, and in the formation of the cover, they are laid with their

meeting edges in overlapped relation and in this position the several sections are vulcanized together to form the top or cover 40 for the umbrella. Each of the sections 9 is provided on its outer edge with a strip of india rubber 12 which serves as a reinforcement for the several sections. The several sections after being secured together 45 and to the cap 11, are placed over the end 14 of the staff, and the outer corners 15 of the triangular members 9 are secured to the ribs 6 by either cotton or wire 16.

By such a construction it will be seen that 50 the top or cover, owing to the meeting edges of the several sections from which it is formed being overlapped when secured together is effectively reinforced at the points where it engages the ribs of the frame thus 55 materially lengthening the life of the cover, as well as forming a cover which will snugly fit the frame when in its expanded position.

Having thus described the invention, what is claimed is:—

A cover for umbrellas having a staff and ribs, said cover comprising a plurality of substantially triangular sections of india rubber, which sections have their side edges vulcanized together to overlie the said ribs 65 in overlapped condition, a reinforcing strip of india rubber vulcanized to the outer edge of the cover to complete the same, and a staff receiving cap arranged vertically of said cover. 70

In testimony whereof I have affixed my signature.

LEON A. SYGLER.
